UNITED STATES PATENT OFFICE

HERMANN OBERLÄNDER, OF ZEULENRODA, GERMANY

KNITTING MACHINE

Application filed April 14, 1927, Serial No. 183,748, and in Germany March 19, 1927.

This invention relates to flat knitting-machines. In order to produce on flat knitting-machines of known type knee-caps, belly-belts and the like, which must have a certain bulging in order that the knitted fabric fits properly on the curvatures of the limb, reversing must be carried out which is troublesome and requires more time, or otherwise expressed the knitting-machine has to carry out more expensive work.

This invention has for its object to improve the construction of the knitting-machine so that this inconvenience is avoided by causing during one carriage-stroke a gradually increasing and then decreasing loop-extension for obtaining a bulging in the knitted fabric and either by making the outer cams move at a certain point of the needle cylinder along a curved guide so that they are shifted with regard to the central cam or by making the needle lengths decrease gradually and then increase gradually at those points at which a bulging has to be produced.

Three forms of construction are shown, by way of example, in the accompanying drawing, in which:

Fig. 1 shows in plan view the preferred form of construction.

Fig. 2 is a cross section on line II-II of Fig. 1.

Figs. 3 and 4 show in plan view the second and third form of construction.

Fig. 5 shows in plan view a fabric knitted according to the invention.

In the Figs. 1 to 4 only those portions of the knitting-machine are shown, which are necessary to illustrate the invention. *a* are the guide-bars for the cam-box *b* with the cams *c*. *d* is a needle-bed.

As shown in Fig. 1 the two outer cams *c* are guided by means of bolts *e* in slots *f* of the cam-box *b*. They are secured in this position by thumb-nuts *g*. In each outer cam *c* a finger *h* is fixed which projects downwards and rests upon a bar *i* fixed on the machine-frame so that it can be turned in its bearing by means of a handle *k*. At that point of the needle-bed at which the bulging of the knitted

fabric has to be produced the bar *i* has a curve *l*.

In the form of construction shown in Fig. 2 the guide-bars *a* for the cam-box *b* have each a curve. In the third form of construction shown in Fig. 3, the needles, at the point in question, are of such lengths that the boundary-line *m* along the heads of the needles is curved.

When the cam arrives at the curve either in the guide bar *i*, the guide bars *a* or the boundary-line *m* of the needle heads, the outer cam *c* must evidently move along these curves when the thumb nuts *g* have been loosened so that at this point a gradually increasing and then a gradually decreasing lengthening of the loops will be produced, from which results the bulging *n* (Fig. 5) in the knitted fabric.

I claim:

1. A flat knitting machine for the production of knee-caps, body-belts and similar goods in which a bulging has to be produced in the knitted fabric, comprising in combination with the needle bed, two outer knocking-over cams, a middle knocking-over cam, and a guide separated from said needle bed having a curve to shift said outer knocking-over cams in regard to said inner knocking-over cam at that point at which a bulging has to be produced in the fabric.

2. A flat knitting machine according to claim 1, comprising in combination with the needle bed, two outer knocking-over cams, a finger downwardly projecting from each of said outer knocking over cams, a middle knocking over cam, and a guide separated from said needle bed having a curve on which said fingers slide to shift said outer knocking over cams in regard to said middle knocking over cam at that point at which in the fabric a bulging has to be produced.

In testimony whereof I affix my signature.

HERMANN OBERLÄNDER.
